CLAIM

The ornamental design for a rack for spice containers, as shown and described.

DESCRIPTION

FIG. 1 is a top plan view of a rack for spice containers showing my new design;

FIG. 2 is a front elevational view of FIG. 1, with the spice containers being shown in broken lines for illustrative purposes only;

FIG. 3 is a side elevational view of FIG. 1;

FIG. 4 is a bottom plan view of FIG. 1;

FIG. 5 is a top plan view of a second embodiment of the design shown in FIG. 1;

FIG. 6 is a front elevational view of FIG. 5;

FIG. 7 is a side elevational view of FIG. 5;

FIG. 8 is a bottom plan view of FIG. 5.

The rear of both embodiments is flat and transparent.
